UNITED STATES PATENT OFFICE.

JOHN H. ALLEN, OF LONDON, ONTARIO, CANADA, ASSIGNOR TO THE MCCLARY MANUFACTURING COMPANY, OF LONDON, CANADA.

ELECTRICAL CONNECTION FOR OVEN ELEMENTS.

Application filed October 16, 1922. Serial No. 594,852.

To all whom it may concern:

Be it known that I, JOHN H. ALLEN, a subject of the King of Great Britain, and resident of the city of London, county of Middlesex, Province of Ontario, in the Dominion of Canada, have invented certain new and useful Improvements in Electrical Connections for Oven Elements, described in the following specification and illustrated 10 in the accompanying drawings, that form part of the same.

The objects of this invention are to overcome the difficulties in connecting oven elements with the wiring terminals and to devise a form of connection which will enable the element being completed before being placed in position and providing a construction which will allow of the element being readily withdrawn at any time without disturbing the rigid electric contacts.

A further object is to enable the electrical connections to be completed from the exterior of the oven structure.

The principal feature of the invention 25 consists in the novel construction and arrangement of parts whereby a plurality of electrical contacts rigidly secured to the removable heating element are adapted to enter fixed contacts arranged in the oven wall 30 in a position accessible from the exterior.

In the drawings, Figure 1 is a horizontal sectional view through my improved contact.

Figure 2 is a vertical sectional view, and 35 Figure 3 is an outside elevational view.

In the construction of electrical stoves it has always been a difficult matter to connect the oven elements with the electrical terminals as the interior of the oven is small and 40 difficult of access and it is very important that the contacts should be very securely fastened because looseness causes arcing and overheating with the consequent destruction of the terminals.

45 Further, it is important that the contacts should be kept free from the steam and grease which permeate the oven and on account of the nature of the heating elements it is desirable that they should be easily and 50 quickly removed for repairs.

In order to accomplish this, I have secured to the heater element an insulating block 1 which carries the terminal contacts 2. These are here shown in the form of flat 55 metal strips rigidly secured to the block by

the screws 3. The strips 2 are provided with binding screws 4 to which the heater elements are connected and the outer ends are preferably turned at right angles forming parallel blades 5.

The oven wall 6 is formed with a recess 7 open at the outer side and having a rectangular shaped hole through the inner wall in which is fitted an insulating block 8 secured by bolts 9. This block is formed with slots 10 which are adapted to receive the contact blades 5, being preferably shaped with flaring openings 11 at the inner side.

Secured to the outer side of the block 8 are a plurality of metal strips 12 which are 70 rigidly fastened to the block by the screws 13. The strips are formed with slots 14 registering with the slots 10 in the block and at each side of the slots is formed a spring finger 15. These spring fingers are adapted 75 to engage an electrical contact with the blades 5 and thus form a very positive connection to the heater element.

The strips 12 are provided with binding screws 16 to which the electric leads are 80 connected. These leads will of course be readily accessible from the outside of the oven.

The recess 7 is preferably covered by a suitable insulating plate 17 and insulating strips 18 are arranged between the strips 12. The several contacts are thus completely insulated, the one from the other and the entire connection is ready of access and may 85 be handled with the greatest ease and safety. 90

Electrical connections may be made independent of the oven elements and the oven elements may be placed in position and removed as desired.

What I claim as my invention is:—

1. An electrical connector for oven elements, comprising an insulating block having openings therethrough, electrical contacts secured on the outer side of said insulating block in alignment with the openings, and electrical contacts secured to the heater element and adapted to pass through the openings in the block and engage the fixed contacts.

2. An electrical connector for oven elements, comprising a block of insulating material having slots therethrough, spring contact members secured to the back of said block either side of each of said slots and having suitable terminals, and rigid contact

2

strips secured to the heater element and adapted to pass through said slots and engage the spring contacts.

3. An electrical connector for oven elements, comprising flat metal strips rigidly secured to the heater element, an insulating block having slots extending therethrough, a plurality of plates secured to the outer

side of said block and having slots registering with the slots in the block and formed with spring fingers arranged in pairs opposite said slots, said strips having suitable terminals, and insulating strips arranged between the aforesaid metal strips secured to said blocks.

JOHN H. ALLEN.
